Patented Dec. 29, 1914.

UNITED STATES PATENT OFFICE.

LACEY BABOS, OF WINSLOW, WASHINGTON.

WRENCH.

1,122,462.

Specification of Letters Patent. Patented Dec. 29, 1914.

Application filed August 24, 1914. Serial No. 858,301.

To all whom it may concern:

Be it known that I, LACEY BABOS, a subject of the King of Hungary, residing at Winslow, in the county of Kitsap and State 5 of Washington, have invented certain new and useful Improvements in Wrenches, of which the following is a specification, reference being had to the accompanying drawings.

10 My invention relates to certain new and useful improvements in wrenches and particularly to that type known as "pipe wrenches," and has for its object the production of a wrench simple in construction at 15 a minimum cost, and one which is not only readily manipulated, but which at the same time is not liable to get out of order.

With these ends in view my invention consists in the details of construction and 20 arrangement hereinafter more fully described.

In order that those skilled in the art to which my invention appertains may know how to make and use my improved wrench, 25 I will proceed to describe the same referring by numerals to the accompanying drawing in which,

Figure 1 is an elevation looking at the front edge of the wrench, the handle being 30 partly broken away, Fig. 2 is a central section taken on line $a-a$ of Fig. 1 and Fig. 3 is a detail side view showing the operative relation of the two jaws.

Similar reference numerals indicate like 35 parts in the several figures of the drawing.

1 is the operating handle terminating at its upper extremity in an angularly disposed fixed jaw 2, the juncture of the rear edge of the jaw with the handle seen at 3 constituting a fulcrum as will be hereinafter explained.

4 is a movable jaw provided on its rear edge with minute serrations 5 preferably of about $\frac{1}{2}$ of an inch, and with a forward 45 projection or beak 6 adapted to overlap the extremity of the fixed jaw as clearly shown in Fig. 2.

7 is a sleeve adapted to embrace the handle and the movable jaw and formed on the interior surface at the back with serrations 8 similar to the serrations 5 on the back edge of the movable jaw 4. The front of this sleeve is inclined to form a space 9 between it and the edge of the handle for the purpose of receiving a spring 10 and also to permit the necessary vibration of the handle

and movement of the sleeve. The handle is formed with a curved slot 11, the center of which is the fulcrum 3 and a pin or screw bolt 12 passing through one or both sides 60 of the sleeve and through the slot 11 fixes the handle in operative relation with the sleeve and also with the movable jaw.

The spring 10 may be located as shown with its free end in the space 9 and in contact with the inner surface of the sleeve 7, and secured at the opposite end to the fixed jaw 2 by a screw 13 or rivet, or if desired the end of the spring may be secured to the handle below the sleeve and with its free end 65 extended upwardly into the space 9, in an obvious manner. This spring, as clearly appears, holds the handle and movable jaw in any adjusted relation by reason of the intermeshing of the serrations 5 and 8, and when it is desired to release this fixed relation between the two members, it is only necessary to press the sleeve against the spring 10 which will cause the back of the sleeve to move out of contact with the serrated edge of the jaw 4, the pin 12 being 70 free to travel in the curved slot 11.

Recurring to the handle 1 with its fixed jaw 2, the extremity of the latter is on a curve the center of which is the fulcrum 3, 85 and this curved surface is serrated as shown in order that a firm hold may be taken upon a pipe. When power and leverage are applied to the handle it vibrates on the fulcrum 3, and moves upon the pin 12 in the 90 slot 11 thus firmly grasping a pipe located between the beak of the jaw 4, and the serrated extremity of the fixed jaw 2.

In applying the wrench to a pipe to be turned, the sleeve 7 is as before stated 95 pressed against the spring whereupon the two jaws may in an obvious manner be adjusted with reference to the pipe, and when the sleeve is released the spring 10 will cause the rear side of the sleeve to embrace the movable jaw and hold it in fixed position. The pipe being now confined between the two jaws and the handle used as a lever having a fulcrum 3, the pipe is firmly gripped and readily turned.

From the construction shown and described it will be seen that my improved wrench comprises only three principal members, the handle and fixed jaw, the movable jaw, and the embracing sleeve secured in 100 operative relation by the spring 10, and pin 12, and that they may be economically man-

ufactured, and expeditiously assembled, and that the several parts are interchangeable if they should become unduly worn or broken.

What I claim as new and desire to secure by Letters Patent is:—

A pipe wrench comprising a handle terminating in an angularly disposed fixed jaw, the juncture between the handle and jaw constituting an angular fulcrum, said handle formed with a curved slot of which the fulcrum is its center; a movable jaw having a beak overlapping the fixed jaw and with its rear edge serrated; a sleeve embracing the handle and movable jaw and with interior serrations meshing with the serrations

on the back of the movable jaw, and inclined at its front to constitute a space between it and the handle, the handle and sleeve connected by a pin passing from the sleeve 20 through the curved slot in the handle; and a spring attached to the handle and with its free end located in the space between the handle and sleeve and bearing against the sleeve, substantially as and for the purpose 25 set forth.

In testimony whereof I hereunto affix my signature in the presence of two witnesses.

LACEY BABOS.

Witnesses:

F. G. KLAUNIG,
G. E. SPAFFORD.
